UNITED STATES PATENT OFFICE.

WILLIAM H. MINER, OF CHAZY, NEW YORK.

RAILROAD DIAPHRAGM-FACE-PLATE-SUPPORTING MEANS.

1,152,036.

Specification of Letters Patent.

Patented Aug. 31, 1915.

Application filed May 4, 1914. Serial No. 836,160.

To all whom it may concern:

Be it known that I, WILLIAM H. MINER, a citizen of the United States, residing at Chazy, in the county of Clinton and State 5 of New York, have invented a certain new and useful Improvement in Railroad Dia- 10 phragm-Face-Plate-Supporting Means, of which the following is a full, clear, concise, and exact description, reference being had 15 to the accompanying drawings, forming a part of this specification.

My invention relates to improvements in means for supporting face plates and parts attached thereto and connected therewith, 15 including buffer stems, in railroad passenger cars.

The invention hereinafter described is an improvement upon the invention disclosed in the patent to me issued August 12, 1913, 20 as Number 1,070,054.

The object of my invention is, to provide an efficient means for supporting face plates and parts connected therewith in railroad cars.

25 In the drawings forming a part of this specification, Figure 1 is an end view of a car body of the type having an end vestibule, and showing the supporting members constituting my invention in position. Fig. 30 2 is a partial cross section taken on line 2-2 of Fig. 1. Fig. 3 is a partial vertical longitudinal section taken on line 3-3 of Fig. 1. Fig. 4 is an enlarged detail illustrating in end view one of the upper brack- 35 ets.

Referring to the drawings, the numeral 5 indicates a car body, 6 the vestibule there- 40 of, 7 the roof, of which the upper deck is indicated by the numeral 8, and the lower deck by the numeral 9. The hood at the end of the upper deck is indicated by the numeral 10. Surrounding the end opening 11 of the vestibule is mounted a diaphragm face plate 12, the lower ends thereof being 45 secured to the face plate 13, and the face plate 13 having connected thereto the buffer side stems 14-14 and the main stem 15. The diaphragm cover 17 is secured between the car body and the diaphragm face plate. 50 The means for supporting the face plate comprises a plurality of rods 18-18, preferably two in number, one mounted at either side of the diaphragm face plate, each being connected at its upper end to a bracket 19 55 secured to the car body by suitable means, preferably the rivets 20-20, and at its lower

end to a bracket 21 secured to the dia- 60 phragm face plate by suitable means, pref- erably the rivets 22-22. Each upper bracket 19 is provided with a track 23 upon 65 which a wheel 24 connected to the upper end of each rod 18 is adapted to run. The said track is formed preferably by the lower inner face of a tube-like member 25 forming a part of the bracket 19, having a longi- 70 tudinal slot 26 along its lower side, and through which the upper end of the rod 18 is adapted to move back and forth, the wheel 24 preferably being in two sections 27-27, one at either side of the upper end of the 75 rod 18, the said wheels being joined by means of a pin or rivet 28 passing through said wheels and the upper end of the rod 18, the said wheels operating on the track 23 formed at either side of the slot 26. Dis- 80 placement of the wheels from their position on the bracket 19 is prevented by the shoul- 85 der 29 with which the outer end of the tube- like member 25 is provided. Each lower bracket 21 is provided with a vertical open- 90 ing 30 for the passage of the lower end of the rod 18, each rod being provided with the nuts 31-31 between which and the lower bracket 21 is seated a spring 32.

On forward movement of the diaphragm 85 face plate, the rod 18 may travel forwardly therewith, the wheel on the upper end thereof of moving forwardly in the bracket 19.

On rearward movement the wheel may move rearwardly within the upper bracket. 90

I claim:

1. In a railroad car, in combination, a car body, a face plate at the end thereof, and means for supporting said face plate, said means comprising rods extending in an up and down direction and having one end of each rod secured to said face plate and the other end of each rod slidably connected to the car body and arranged to move back and forth horizontally relatively to said car body. 95

2. In a railroad car, in combination, a car body, a face plate, and means for sup- 100 porting said face plate, said means includ- ing brackets, a rod depending from each bracket, each rod being slidable with respect to its corresponding bracket and in a direction longitudinally of the car, and yield- able connections between the lower end of each of said rods and the face plate. 105

3. In a railroad car, in combination, a car having a vestibule, a face plate, and 110

- means for supporting said face plate, said means comprising a pair of brackets, one on each side of the vestibule and secured to the car, each bracket having a track, a roller mounted to move back and forth on each of said tracks, a supporting rod depending from and connected to each of said rollers, and yielding connections between the lower ends of each of said rods and the face plate.
- 10 4. In a railroad car, in combination, a car body, a face plate, rods, brackets and wheels, each rod being connected at one end to the face plate, the brackets being rigidly connected to the car body and extending lengthwise of the body, each rod having a wheel at its upper end engaging the bracket and slidable back and forth toward and from the car.
- 15 5. In a railroad car, in combination, a

car body, a face plate, and means for supporting the same, said means comprising rods connected to the face plate, and brackets, each of said brackets having a tube, the rods being provided at their upper end with wheels, the said wheels operating in said tubes.

6. In a railroad car, in combination, a car body, face plate, rods connected to the face plate, brackets and wheels, each bracket having a tube to receive a wheel, each tube being provided with a slot for the passage of one of the rods, a wheel being mounted on each rod within the tube.

WILLIAM H. MINER.
